UNITED STATES PATENT OFFICE.

CHARLES A. BELKNAP, OF NEW YORK, N. Y., ASSIGNOR OF ONE-HALF TO
CHARLES E. PARSONS, OF SAME PLACE.

MACHINE FOR ADDRESSING ENVELOPS OR WRAPPERS.

SPECIFICATION forming part of Letters Patent No. 628,385, dated July 4, 1899.

Application filed August 9, 1898. Serial No. 688,165. (No model.)

To all whom it may concern:

Be it known that I, CHARLES A. BELKNAP, a citizen of the United States, residing at New York, borough of Brooklyn, State of New York, have invented certain new and useful Improvements in Machines for Addressing Envelops or Wrappers, of which the following is a specification.

This invention relates to that class of machines for addressing wrappers, envelops, &c., in which a perforated stencil-card is used; and the object of the present invention is to render this class of machines more compact and light, so that they can be readily transported by hand from place to place.

The invention consists of a suitable frame, a movable stencil-carrier mounted on said frame and provided with ways along which the perforated stencil-cards are caused to travel, a supporting plate or bed upon which the articles to be addressed are placed, a laterally-movable impression-roll, means for moving said roll, an ink-reservoir in which an inking-roller turns, means for intermittently turning said roll, a transfer-roll adapted to transfer the ink from the inking-roll to the impression-roll, and means for oscillating said transfer-roll, as will be hereinafter described and then particularly pointed out in the claims.

In the accompanying drawings, Figure 1 is a side elevation of my improved machine for addressing wrappers, envelops, &c. Fig. 2 is a plan view of the same. Fig. 3 is a vertical longitudinal section on the line 3 3 of Fig. 2, parts being in elevation. Figs. 4 and 5 are transverse sections on lines 4 4 and 5 5, respectively, Fig. 1. Fig. 6 is an enlarged detail view, in longitudinal section, through the stencil-carrier, the inking mechanism, and adjacent parts, parts broken away. Fig. 7 is a broken detail section of the lower portion of the collecting-box for the perforated stencil-cards. Figs. 8 and 9 are detail end views of the inking mechanism, looking toward the opposite side of Fig. 4. Figs. 10, 11, 12, and 13, inclusive, are detail views, partly in side elevation and partly in section, of the pusher mechanism.

50 Similar letters indicate corresponding parts. A indicates the frame of the machine, which

at one end is provided with an elevated impression bed or table A', while at the other end of the frame, in suitable bearings a, is journaled the driving-shaft B, on which is fixed, 55 at about the mid-length of the machine, a large cylinder-cam C, which is provided with cam-grooves C' C², respectively, while between the cylinder-cam C and the belt-pulley B' is placed a smaller cylinder-cam D, provided with a 60 cam-groove d. These cams effectuate the operation of all of the working parts of the machine through the medium of certain instrumentalities now to be described.

At the upper part of the frame A are located 65 longitudinal guide-rails E, upon which are guided the transverse slides F F', which are provided with pins f f', respectively, upon which are placed suitable antifriction-rollers and that are received in the cam-grooves C' C², 70 respectively. The slide F is provided with a bifurcated bracket or fork F², which engages a stud g on one end of a reciprocating rack-bar G, that is suitably guided along one side of the stencil-carrier H, which is pivoted 75 at h to the bracket H' of the frame A. The stencil-carrier H extends approximately from end to end of the machine, and its rearwardly-projecting end is connected by toggle-links I with the frame A of the machine, so that 80 through the medium of the slide J, which has a pin-and-slot connection j with the toggle-joint and the pin j', which takes into the cam-groove d of the cam D, the said stencil-carrier is oscillated at the proper moment of time. 85 The companion slide F' of the slide F is provided with upwardly-extending forks or bifurcated brackets F³, which engage with studs k on the rear ends of reciprocating bars K, that are suitably guided on the stencil-carrier 90 and are connected by a shaft K², journaled therein, and which passes through slots l' in the sides of the stencil-carrier. The shaft K² carries at one end a gear-wheel K', which meshes with the teeth of rack-bar G, and also 95 carries a suitable impression-roll L, which moves between the sides of the stencil-carrier and is adapted to travel over the surface of the impression bed or table A' when the stencil-carrier is pressed down upon the same. 100

Upon the rear part of the stencil-carrier H the receiving-box M for the perforated sten-

cil-cards *m* is arranged; but I do not limit myself to this arrangement, inasmuch as instead of moving with the stencil-carrier it is evident that the said receiving-box can be supported in stationary position similarly to the collecting-box *N*, which is supported at the front end of the machine by means of a suitable arm *N'*, extending upwardly from the frame *A*. This alternative arrangement of the box *M* is evident without any detailed illustration.

Extending along the sides of the stencil-carrier from a point below the receiving-box *M* are ways *h*², along which the perforated stencil-cards *m* are adapted to be moved until the forward card arrives between the impression-bed *A'* and the collecting-box *N*. The cards *m*, being of the usual formation—that is to say, with an exterior frame of pasteboard, onto which is pasted a sheet of parchment—are adapted to be pushed along the ways *h*² by means of suitable pusher mechanism, the pusher of which engages with the inner edge of the exterior frame, thereby avoiding injury to the outer edge of the same. The pusher mechanism consists of a transverse slide-plate *O*, which extends from one side toward the other side of the stencil-carrier and to which is pivoted a push-pawl *O'*, one end of the transverse slide *O* being provided with a shoe *O*², which is guided on a suitable guide-rail *h*⁴ on the side of the stencil-carrier. Fixed to the shoe *O*² by means of a suitable pin-and-slot connection *p* is a cheek-plate *P*, which is adjustable upon the shoe so as to limit the stroke of the push-pawl, said cheek-plate being provided with a transverse slot *p'*, which receives a stud or pin *p*², projecting inwardly from the rear end of the reciprocating rack-bar *G*. The object of this pin-and-slot connection *p* *p*² is to cause the push-slide to be moved together with the rack-bar *G*, for if this connection were not provided it will be seen that the inclined arrangement of the ways *h*⁴ for the push-slide would prevent the working of the same. The object of this inclination of the ways *h*⁴ is to prevent the interference of the cheek-plate *P* with the longitudinally-reciprocating bars *K* of the impression-roller.

50 A projection *p*³ on the cheek-plate *P* is guided in a longitudinal groove *p*⁴ in the bar *K*, so as to hold the same down during its reciprocation and to prevent the release of studs *k* from the forks *F*³.

55 Supported on the stencil-carrier between the receiving and collecting boxes is the reservoir *Q* in suitable bearings, of which an inking-roll *Q'* is adapted to turn, said inking-roll being provided with an exposed portion, over which the ink is kept equally distributed by means of suitable doctors *q* *q*. Referring particularly to Figs. 8 and 9 in connection with Figs. 3 and 6 it will be seen that at one end of the inking-roll *Q'* is arranged a ratchet-wheel *R*, that turns with the roll and the teeth of which are adapted to be engaged by a spring-actuated pawl *r*, that is pivoted to

the outer end of an oscillating arm *R'*, that turns freely upon one of the trunnions of the said inking-roll. The oscillation of the arm *R'* and the resulting intermittent rotation of the inking-roll *Q'* are effectuated by means of an angular cam *S*, which is fixed by suitable fastening screws or rivets *S'* to one of the reciprocating bars *K* of impression-roll *L*. The inclined surface of the cam *S* works against an antifriction-roller *t*, which is journaled on a pin *t'*, projecting from the oscillating arm *R'*. Pivoted at *u* to the stencil-carrier *H* are arms *U*, in the outer ends of which the transfer-roll *V* is journaled, while supported by a side extension *W* of one of the arms *U* is a projecting tappet-arm *W'*, which carries at its free end an antifriction-roller *W*², adapted to be engaged by means of an angular cam *X*, which is firmly fastened to one of the longitudinally-reciprocating bars *K* in such position that as the impression-roll *L* travels forward the said cam *X* causes the transfer-roll to be pressed up in contact with the inking-roll *Q'*, so as to receive the ink while the impression is being made by the impression-roll.

The operation of the machine is as follows: The appropriate stencil-cards *m*, according to the addresses which are to be printed, are placed in the receiving-box *M*. The other parts of the apparatus being in proper order, the mechanism is set in motion. A wrapper or envelop is now inserted between the stencil-carrier and the impression-bed *A'* and placed on the latter after the forward stencil-card has been pushed forward and while the stencil-carrier *H* is raised. During the lowering of the stencil-carrier through the medium of its oscillating cam *D* the rack-bar *G* is moved forward, at the same time causing the push-pawl *O'* to push forward the lower card located in the receiving-box *M* or at the rear end of the ways in which the stencil-cards are guided. The cam-grooves *C*' *C*² of the cam *C* are so formed as that at the proper time—that is to say, at the moment of dwell of the stencil-carrier upon the impression-bed *A'*—the reciprocating bars *K* through the medium of the slide *F'* are pushed forward, thereby causing the impression-roll *L* to travel over the stencil-card along the same and to press the ink through the perforations in the same, thus imprinting the address upon the article placed upon the impression-bed *A'*. At the moment that the impression-roll *L* is traveling forward over the impression-bed *A'* the transfer-roll *V* is being moved up in contact with the surface of the inking-roll so as to receive the ink. Just before the stencil-carrier *H* rises the reciprocating bars *K*, which support the impression-roll *L*, are moved back with said roll, thereby again turning the impression-roll, imparting a double impression to the stencil-card, and permitting the lowering of the transfer-roll *V*, so that it is thereby brought in contact with the surface of the impression-roll. When the stencil-carrier *H* is rising, the rack-

bar G is being moved back, thereby turning the impression-roll in contact with the transfer-roll, so as to transfer the ink onto the impression-roll.

5 The play of the stencil-carrier is limited between the impression-bed A' and the collecting-box N, and when the stencil-carrier arrives at the limit of its upward movement the stencil-card which has been used is snapped 10 in between the downwardly-projecting spring-catches N², arranged on the said collecting-box, (see Figs. 6 and 7,) so that the said catches take up each stencil-card as the stencil-carrier is moved up against the said collecting-box. By the above-described construction machines for addressing wrappers, envelopes, &c., are rendered more compact, and by the employment of the cams the parts are so properly timed in their movements as that 20 the reliable working of the machine is produced. After the cards have all been used up they will have been transferred to the collecting-box, from which they are then removed, a new supply of cards being then placed in the 25 receiving-box.

It is evident that various changes in the construction and arrangement of the parts will suggest themselves to skilled mechanics, and I do not therefore limit myself to the construction shown and described, as any machine which will accomplish the work done by the machine in a similar manner is within the province of my invention.

Having thus described my invention, I 35 claim as new and desire to secure by Letters Patent—

1. In a machine for addressing envelops or wrappers, the combination, with an impression bed or table, of a stencil-carrier movable 40 relatively to the same, and provided with ways along which the stencil-cards are adapted to be fed, and means coöperating with the stencil-cards for printing upon the article placed upon the impression bed or table, substantially as set forth.

2. In a machine for addressing envelops or wrappers, the combination, with an impression bed or table, of an oscillating stencil-carrier provided with ways for the stencil and 50 cards, means for oscillating said stencil-carrier, means for moving the cards along in said ways, and means coöperating with the cards for producing the impression upon the envelop or wrapper, substantially as set forth.

3. In a machine for addressing envelops or wrappers, the combination, with an impression bed or table, of a movable stencil-carrier, an impression-roll carried by the stencil-carrier, means for feeding the stencil-cards over 60 onto the impression-bed, and means for moving the impression-roll along said stencil-carrier, and over said impression-bed, substantially as set forth.

4. In a machine for addressing envelops or 65 wrappers, the combination, with an impression bed or table, of a movable stencil-carrier, provided with ways for the stencil-cards, a

pusher guided on said stencil-carrier for pushing the cards along toward the outer end of the stencil-carrier, and means coöperating 70 with the cards for producing the impression upon the envelop or wrapper, substantially as set forth.

5. In a machine for addressing envelops or wrappers, the combination, with an impression bed or table, of a movable stencil-carrier 75 provided with ways for the stencil-cards, means for causing said cards to produce an imprint, and a collecting-box for the cards, said stencil-carrier being arranged to move 80 between the impression-bed and collecting-box, substantially as set forth.

6. In a machine for addressing envelops or wrappers the combination, with an impression bed or table, of a movable stencil-carrier 85 provided with ways for stencil-cards, a receiving-box communicating with said ways, means for feeding the cards along said ways, means for causing said cards to effectuate an imprint, and a collecting-box for the cards, 90 arranged over said impression-bed, substantially as set forth.

7. In a machine for addressing envelops or wrappers, the combination, with an impression bed or table, of a collecting-box for the 95 used cards, a stencil-carrier movable between said bed and collecting-box, means for coöperating with the cards to produce the impression, and means for removing the cards from the stencil-carrier to said collecting-box, 100 substantially as set forth.

8. In a machine for addressing envelops or wrappers, the combination, with an impression bed or table; of a movable stencil-carrier, inking mechanism provided with a transfer-roll, an impression-roll supported by and guided on the stencil-carrier and adapted to receive ink from said transfer-roll, and means for operating the inking mechanism and impression-roll at properly-timed moments, substantially as set forth.

9. In a machine for addressing envelops or wrappers, the combination, with an impression bed or table, of a movable stencil-carrier, an impression-roll-inking mechanism supported by the stencil-carrier, a transfer-roll between the inking mechanism and impression-roll, and cams for working the stencil-carrier, the inking mechanism, the transfer-roll and the impression-roll at properly-timed moments, substantially as set forth.

10. In a machine for addressing envelops or wrappers, an oscillatory stencil-carrier provided with suitable ways for stencil-cards, and an impression-roll movable parallel with 125 said ways, substantially as set forth.

In testimony that I claim the foregoing as my invention I have signed my name in presence of two subscribing witnesses.

CHARLES A. BELKNAP.
